UNITED STATES PATENT OFFICE

AUGUSTIN J. CHEVRETT, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

SHUTTLE CHANGING LOOM

Application filed April 23, 1929, Serial No. 357,548. Renewed April 7, 1931.

This invention relates to a loom in which mechanism is provided for automatically replacing an exhausted shuttle during the continued operation of the loom. A loom of this type is shown in my prior application, Serial No. 196,378, filed by me June 3, 1927, and it is the general object of my present invention to improve the construction therein shown, to the end that the shuttle transfer may be more effectively completed and that the transfer operation may be performed at a higher speed.

A more specific object of my invention is to provide means by which the fresh shuttle is positively seated in the regular shuttle box immediately after transfer thereto.

In the preferred form of my invention, I provide a hinged cover for the regular shuttle box, together with cam means for positively raising and lowering said cover as the box is presented to the shuttle storage magazine and is thereafter removed therefrom.

My invention further relates to arrangements and combinations of parts which will be hereinafter described and more particularly pointed out in the appended claims.

A preferred form of the invention is shown in the drawings in which

Fig. 1 is a front elevation of parts of a loom embodying my improvements;

Fig. 2 is a left hand side elevation, looking in the direction of the arrow 2 in Fig. 1;

Figs. 3 and 4 are partial plan views, taken along the line 3—3 and 4—4 in Fig. 2 respectively;

Figs. 5, 6, 7 and 8 are diagrammatic sectional elevations of the storage magazine and shuttle boxes, showing the same in certain successive relations assumed thereby during shuttle transfer; and

Fig. 9 is a detail sectional elevation of the boxes, taken along the line 9—9 in Fig. 4.

Referring to the drawings, I have shown a portion of a loom frame 10, a lay 11, and a drop box frame 12 (Fig. 2) mounted on the usual lifter rod 13 and raised and lowered by a cam 14 on the usual bottom or cam shaft 15 of the loom.

The cam 14 engages the rear end of an actuating lever 16, mounted on a fixed pivot

at 17 and movable alongside a lifting lever 18, connected by a link 19 to a stud at the lower end of the lifter rod 13. A latch 20 is mounted on the forward end of the actuating lever 16 and may be projected by suitable pattern mechanism to a position in which it will engage the lifter lever 18 and form an operative connection between the lever 16 and the lever 18. A spring 21 holds the rear end of the lever 16 yieldingly in contact with the cam 14.

The parts thus far described are of a usual type and in themselves form no part of my present invention.

The drop box frame 12 (Fig. 9) is formed to provide an upper regular shuttle box 25 and a lower or auxiliary shuttle box 26. A binder 28 and binder spring 29 are mounted on a fixed part of the lay end and remain at a fixed elevation relative to the shuttle race, so that the binder 28 is in position to co-operate with a shuttle in running position, whether it is in the regular or auxiliary shuttle box.

At its extreme inner end, the regular shuttle box 25 is substantially closed at its top, as indicated at 30 and 31 in Figs. 4 and 9, these parts being separated by a relatively narrow thread passage 32. Throughout the greater portions of its length, however, the regular shuttle box 25 is entirely open at the top. The box 25 is provided with a plate or cover 35, mounted on a rod or shaft 36 which extends longitudinally of the shuttle box 25 and which is supported in bearings 37 and 38 formed on said box.

A coil spring 40 (Fig. 4) encircles the end of the rod 36, the spring being connected at one end to the bearing 38 and at the other end to a collar 42 angularly adjustable on the rod 36. The spring 40 may be adjusted to provide any desired spring tension to close the cover 35 downward on the shuttle box 25.

A shuttle storage magazine 44 (Fig. 2) is mounted in fixed position on a bracket 45 secured to the loom side 10. The magazine is of such vertical extent as to receive and hold five or six fresh shuttles in reserve. At its front portion, the magazine is cut away, as indicated at 46 and 47 in Fig. 3, thus

making the shuttles in the magazine more readily accessible and also allowing the weft ends W to be drawn freely outward to a suitable end holder 48 (Fig. 4).

5 The magazine 44 has a bottom plate 50 (Fig. 2) mounted on a pair of swinging arms 52, one at each end of the magazine and each pivoted to a stud 54 fixed near the top of the magazine. A spring 56 is inserted between 10 a lug or projection 57 on one of the arms 52 and a lug 58 on the magazine 44. The spring 56 acts to swing the plate 50 to operative or magazine-closing position, which position is determined by a set screw 59 on one 15 of the arms 52, which may be adjusted to engage the rear face of the magazine 44.

The normal position of the bottom plate 50 is indicated in Figs. 2, 5 and 7, and the rearward or inoperative position thereof is 20 indicated at Fig. 6. Bolts 60 and 61 are adjustably secured in the arms 52 which support the plate 50 and are engaged by portions of the shifting shuttle boxes as the latter are moved rearward in raised position at 25 the time of transfer.

A cam member 65 (Fig. 2) is secured in fixed position on the front of the magazine 44 and is so located that it will co-operate 30 with a cam roll 67 mounted on a lug 68 projecting upward from the plate or cover 35.

Having described the details of construction of my improved loom, the method of operation thereof is as follows:—

35 During the normal running of the loom, the shuttle boxes are in lowered position and the regular shuttle box 25 is in alignment with the shuttle race on the lay 11. Upon indication of weft exhaustion, the shuttle boxes are raised while the shuttle 40 is at the opposite end of the loom. Upon its return, the shuttle S is received in the lower or auxiliary shuttle box 26.

The boxes are closed at their back sides by a plate 70 (Fig. 4) mounted in fixed position 45 on the lay 11 and the shuttle S is received between this plate 70 and the binder 28 which is also fixed in vertical position.

The lower or auxiliary box 26 has no bottom, however, and as the boxes next move 50 downward, the shuttle S is released from the binder 28 and falls into a chute or guide-way 75, inclined forward and downward and guiding the exhausted shuttle to a suitable receptacle or support.

55 In the meantime, the regular shuttle box 25 has been raised, carrying the cam roll 67 on the box cover 35 into position for engagement by the fixed cam plate 65. Such engagement swings the cover 35 forward and upward, as indicated in Fig. 6, while at the same time the raised shuttle box 25 in its rearward movement engages the bolts or stops 60 and 61 on the arms 52 and thus opens the lower end of the magazine, as also indicated in Fig. 6.

The lowermost shuttle S' in the magazine 44 moves downward when released by the plate 50 and is received in the regular shuttle box 25, while the latter is in its raised position.

70 As the lay thereafter moves forward, the cam roll 67 travels downward in the groove in the cam plate 65 and the cover 35 is thus positively forced downward by cam action to close the box during the initial forward 75 movement of the lay.

The shuttle S' is thus very effectively and firmly seated in the regular shuttle box 25 and is thereafter held therein by the cover plate 35, which is yieldingly held closed by the spring 40 after release from the cam plate 65. During this cover-closing operation, the parts assume the successive positions shown in Figs. 7 and 8 and continued downward movement brings the regular box back to the 85 position shown in Fig. 5.

80 When the boxes reach this position, the auxiliary box is below the binder 28 and the exhausted shuttle S is free to drop into the chute or guide 75. Also as the lay moves forward, the bottom plate 50 returns to its original position, preventing downward movement of the next shuttle S' in the magazine, which has now become the lowermost shuttle.

85 I have thus provided extremely simple 90 mechanism by which a fresh shuttle can be released from storage and inserted in place of the running shuttle upon indication of weft exhaustion, and by which it can be firmly and positively seated in the regular shuttle box before the boxes return to running position and before the new shuttle is picked therefrom.

95 Both the opening and closing of the cover plate 35 is accomplished by positive cam action and on this account it is found that a loom provided with my improved replenishing mechanism can be operated at a very substantial increase in speed over that which would be permitted with the construction 100 shown in my previous application.

105 Having thus described my invention and the advantages thereof, I do not wish to be limited to the details herein disclosed, otherwise than as set forth in the claims, but what I claim is:—

110 1. In a shuttle changing loom, a regular 115 shuttle box, an auxiliary shuttle box positioned beneath said regular shuttle box, a cover hinged on said regular shuttle box, a shuttle magazine, means to present said regular shuttle box to said magazine by an upward and rearward movement, and cam means effective to positively raise and 120 positively lower said cover as said regular shuttle box approaches and recedes from said magazine.

125 2. In a shuttle changing loom, a regular 125 shuttle box, an auxiliary shuttle box positioned beneath said regular shuttle box,

means to insert a fresh shuttle in said regular box, and cam means effective to positively push said shuttle firmly downward to its seat in said shuttle box.

5 3. In a shuttle changing loom, a regular shuttle box, an auxiliary shuttle box positioned beneath said regular shuttle box, a cover for said box, and positively acting means effective to force said cover downward on said box and to seat a shuttle freshly inserted therein.

10 4. In a shuttle changing loom, a regular shuttle box, an auxiliary shuttle box positioned beneath said regular shuttle box, a cover normally closing the top of said regular box, a storage magazine for fresh shuttles, means to move said regular box upward and rearward to a position under said magazine in which it receives a shuttle from said magazine, and positively acting means effective to swing said cover upward and forward from said box as said box is moved upward and rearward and to positively close said cover downward on said regular shuttle box as said box is moved forward and downward from said magazine.

15 In testimony whereof I have hereunto affixed my signature.

AUGUSTIN J. CHEVRETTE.
